(57) **CLAIM**

The ornamental design for a cap for a marking pen, as shown and described.

DESCRIPTION

FIG. 1 is a perspective view of a cap for a marking pen, according to the invention.

FIG. 2 is a front view of the design according to the invention.

FIG. 3 is a rear view of the design according to the invention.

FIG. 4 is a side view of the design according to the invention.

FIG. 5 is a top view of the design according to the invention.

FIG. 6 is a bottom view of the design according to the invention; and,

FIG. 7 is a cross-sectional view of the design taken along line 7—7 as shown in FIG. 6.

The broken lines are for the purpose of illustrating environmental matter and form no part of the claimed design.
